EDWIN G. VAN WIE AND RANSOM W. DAVENPORT, OF DETROIT, MICHIGAN, ASSIGNEES
TO DETROIT STOVE WORKS, OF DETROIT, MICHIGAN, A CORPORATION OF MICHIGAN.

ELECTRIC RANGE.

1,148,639.

Specification of Letters Patent. Patented Aug. 3, 1915.

Application filed November 25, 1912. Serial No. 733,510.

To all whom it may concern:

Be it known that we, EDWIN G. VAN WIE and RANSOM W. DAVENPORT, citizens of the United States of America, residing at Detroit, in the county of Wayne and State of Michigan, have invented certain new and useful Improvements in Electric Ranges, of which the following is a specification, reference being had therein to the accompanying drawings.

The invention relates to electrical heaters and has for one of its objects the obtaining of a construction similar in its organization to the ordinary gas range.

It is a further object to simplify the construction and to render the various heating units readily detachable and exchangeable to facilitate repair.

Still further it is an object to utilize a metallic frame and to a large extent metallic parts, while at the same time conserving the heat developed in the units and avoiding waste by conduction or radiation.

With these objects in view the invention consists in the construction as hereinafter set forth.

In the drawings: Figure 1 is a perspective view of the range. Fig. 2 is a diagram showing the arrangement of the electrical circuits. Fig. 3 is a longitudinal section through one of the units. Fig. 4 is a detached perspective view of one of the oven units. Fig. 5 is a sectional perspective view of the switch showing the arrangement of clamping contacts.

In the present state of the art, electrical cooking stoves are usually constructed along radically different lines from gas ranges, and the relative disposition of the ovens, top, heaters, etc., is also different. As a consequence the substitution of an electric stove for a gas range requires a certain amount of special training of the user. With our improved construction the lines of the range and the disposition of the oven and surface heaters is substantially the same as with a gas range. Thus a common form of construction in a gas range is to provide an open top or hot plate, having a plurality of burners, and to arrange the baking oven and broiler in superposed relation at one side of said hot plate, this arrangement being followed in our improved construction.

In detail, A is a metallic frame similar to

constructions ordinarily employed in gas ranges.

B is the broiling oven, and C the baking oven, arranged the one over the other and at one side of the hot plate or open top B'.

E are electrical controlling switches for the various heaters, which are mounted upon the frame, preferably adjacent to the front rail of the open top. These switches control not only the units which are employed in connection with the open top or hot plate, but also the several units arranged in the broiling and baking ovens, and the construction is also such that the heat may be varied by different positions of adjustment of each switch. To permit exchanging the units they are detachably mounted in their various positions and the construction is such that the placing or the removal of the unit will automatically make or break the electrical connections thereto. To further facilitate the operation of exchange, the units are so constructed that they may be inserted or removed without the use of tools, in substantially the same manner as the detachable burners of a gas range.

In detail, F are the heating elements of the open top or hot plate, and are preferably of disk form, and are mounted upon a supporting frame G which has a laterally-extending arm H. The electrical conductors for the heating elements extend along the arm H and at the outer end of the latter are connected to terminal contacts I having an insulating mounting upon said arm. Directly beneath the disk the frame G is supported upon a cross-rod J through the medium of a notched yoke K, while the outer end of the arm H is mechanically supported by the insertion of the terminal contacts I into a socket connector on the frame. Thus the engagement is such that one familiar with the care of a gas range and accustomed to removing the gas burners for cleaning, can readily attach or detach the heating units.

The terminal socket with which the contacts I of each unit are engaged is preferably an integral part of the switch block E which controls the current. To this end said switch is provided with an insulator base having the switch proper mounted thereon, and provided on its rear side with socket contacts L complementary to the pin

contacts I. The block is also preferably provided with fuse sockets M for detachably inclosed fuses M', so that the circuit for each separate unit is protected by its own fuse. The blocks E for the various switches are placed adjacent to each other and all are connected to common service conductors N, which pass through grooves in the blocks and are coupled by clamps O. The blocks E are preferably mechanically supported by having a grooved engagement with a rod P extending parallel with the side rail of the frame and attached thereto by a suitable bracket P'. At the side of the frame a fuse block or cut-out Q for all of the circuits may be arranged, and may be connected to the conductors N and to conductors R passing through a suitable conduit R' to the source of supply. The disks F are arranged around at different points within the frame and are preferably surrounded by top plates S, which are marginally supported upon the frame and are apertured for the several disks. These top plates inclose and protect the portions of the units below the top, and, being preferably on the same level as the disks F and frame, produce a flat closed top. The oven heating units are preferably formed as shown in Fig. 4, and consist of supporting rods T, which are inserted through apertures in the side wall of the oven and which carry the electrical resistor T'. The rods T, which are preferably formed of insulating material or material having an insulating coating, are mechanically supported by blocks or heads T² at one end thereof engaging recesses in the side wall of the oven. Electrical connection is made by the insertion of the units through contact members U on the heads T² which engage socket contacts in blocks U'. The latter are arranged in the recess U² along the side of the oven, and the several blocks are connected with the conductors leading to the controlling switch. In order that varying temperatures may be obtained, we preferably use a three-wire system for connecting the blocks U', so that the resistors T' of the several units are alternatively connected between two of said wires and the third wire. As shown in the diagram, three units are employed in the upper oven, and five in the lower oven, these units being alternatively connected between the conductors V V' and the conductors V' V². These three conductors lead to their controlling switch E, and the arrangement is such that in one position of the switch the units between the conductors V and V' are in circuit; in another position the units between the conductors V' and V² are in circuit; and in a third position all of said units are in circuit; thereby giving considerable range in variation of the temperature.

65 The detail construction of the heating

units, controlling blocks and the ovens form subject matter for other applications and are not a part of the present application.

In operation the switches E, being arranged in substantially the same relation as the valves of a gas stove, the operator may conveniently control any of the units for the open top or for the oven. The temperature may be varied by the turning of the switches to different points so that either low or high temperatures may be used as desired. If at any time one of the units for the open top becomes inoperative, all that is necessary to replace it is to remove the top plate S and to lift the disk portion of the unit, so as to disengage the notched yoke K from the supporting bar J, after which the contacts A may be withdrawn from their sockets, thereby breaking the electrical connection and freeing the unit. In like manner a new unit may be quickly inserted without any special skill on the part of the operator or any knowledge of electrical science. When in use, there are no live wires or contacts which are exposed, which eliminates the possibility of receiving a shock or forming a short circuit.

What we claim as our invention is:

1. An electrical cooking range comprising a frame having an exposed top section and an oven at one side thereof and above the same, independent electrical heating units for said exposed top and oven, and a series of switch blocks provided with switching devices detachably engaging the front rail of the frame for controlling the units of the oven and frame.

2. An electrical cooking range, the combination of an open top section, an oven section arranged at one side thereof and extending thereabove, switch blocks provided with switches arranged along the front rail of the open top section electrically connected to certain of said switches, electrical heating units for said open top section, a cross bar carried by the frame and extending across the said open top section for supporting the heating units, electrical heating units for said oven laterally insertible thereinto from the side adjacent the open top, electrical connections for said units, and controlling switches for the said units.

3. An electrical cooking range, the combination of an open top section, an oven section arranged at one side thereof and extending thereabove, switch blocks provided with switches detachably engaging the front rail of the open top section, electrical heating units in said top section electrically connected to certain of said switches, electrical heating units for said oven sections laterally insertible thereinto through the side adjacent to said open top section, apertured terminal blocks through which said units are insertible, located in a groove in the said

side of the oven, electrical conductors between said terminal blocks and their controlling switches, and a cover for the channel in the oven side, concealing said terminal blocks, and heating blocks connected therewith.

4. In an electrical cooking range the combination of an open top section, an oven section arranged at one side thereof, electrical controlling switches arranged along the front rail of said open top section, electrical heating units in said open top section, electrically connected to certain of said switches, electrical heating units for said oven laterally insertible thereinto from the side adjacent to said open top, and electrical connections housed within one of the rails of said open top section and extending to the oven section whereby they may be detachably engaged.

5. An electrical cooking range comprising an open top section, an oven section arranged adjacent to one side of said open top section and extending thereabove, electrical switches arranged along the front rail of said open top section, electrical heating units for said open top section connected to certain of said switches, electrical heating units for said oven section laterally insertible thereinto through the side adjacent to said open top section, apertured terminal blocks, through which said units are insertible located in a groove in said side of the oven, electrical conductors between said terminal blocks and their controlling switches, and a removable cover for the channel in the oven side concealing said terminal blocks and heating units connected therewith.

40 6. An electrical cooking range comprising an open top section, an oven section adjacent to one side of said open top section and containing superposed oven chambers with portions of both chambers extending above the level of said open top, electrical heating units for the upper and lower oven chambers laterally insertible through apertures in the side wall adjacent to said open top, apertured terminal blocks through which said heaters are insertible located in grooves in said oven side, conductors connecting through said terminal blocks and extending longitudinally of said grooves, cover plates for said channels removable for the insertion or withdrawal of said units, electrical switches arranged along the front of said open top section, and electrical connections between certain of said switches and said conductors in said channels.

65 7. An electrical cooking range comprising an annular frame, a plurality of electrical heating units arranged within said frame and having their heating surfaces substantially in the plane of the top of

said frame, lateral arms on said units extending to the front of said frame, controlling-switch blocks mounted on the front rail of said frame, and coöperating terminal contacts on said blocks and lateral arms of said heating units for electrically and mechanically connecting the same. 70

8. An electrical cooking range comprising an open frame, disk heating units arranged within said frame, rods extending 75 across said frame upon which said units are supported, lateral arms upon said units extending to the front of said frame, controlling-switch blocks mounted on the front of said frame, and laterally engageable contacts upon said switch blocks and lateral arms for electrically and mechanically connecting said units to said switch block. 80

9. In an electrical cooking range, an open frame, a disk unit within said frame having its upper face in the plane of the top of the frame, a lateral arm on said unit extending to the front of said frame, a controlling switch block mounted at the front of said frame, laterally-engageable co-operating contact members on said lateral arm and switch block for electrically and mechanically connecting said disk unit to said block, a cross-rod beneath said disk for directly supporting the same, and a cover plate or panel fitting within said frame and apertured to receive said disk heating unit. 85 90 95

10. In an electrical cooking range, an open frame, electrical controlling switch blocks arranged along the front of said frame, parallel guides at the front of said frame with which said blocks slidably engage, conductors extending parallel to said guides, clamping terminals on said blocks for connecting the same to said conductors, 100 disk heating units within said frame, rods upon which said units are supported, lateral arms extending from said units to the respective switch blocks, and coöperating contact members on said switch blocks and lateral arms for mechanically and electrically connecting the same. 105 110

11. An electrical cooking range including an open frame, a cover plate at the top of the frame provided with openings, a plurality of disk heating units arranged in said openings, a rod extending across said frame at the rear thereof to support the heating units, each of said heating units having at its under side a yoke engaging the said rod and a supporting arm extending to the front of said frame, controlling switch blocks extending along the upper front rail of said frame, and means for detachably connecting the front end portions of said arms with the switch blocks. 115 120 125

12. An electrical cooking range including a substantially rectangular frame, an oven secured to the frame and including superposed heating chambers, the frame being 130

- disposed at the base of the lower chamber, a cover plate for the top of the frame formed with a plurality of openings; disk heating units arranged within said openings, a rod connecting the under side of the frame adjacent the oven and forming a support for the heating units, each of said heating units being provided with a yoke which engages the rod and a supporting frame which extends toward the front of the frame, the front of the frame being grooved to receive
- 5
- 10

a plurality of switch blocks, the arms being insertible through the frame whereby they may be connected to the switch blocks.

In testimony whereof we affix our signatures in presence of two witnesses.
